US00D748603S

(12) **United States Design Patent**
Kwan et al.

(10) **Patent No.:** **US D748,603 S**
(45) **Date of Patent:** **** Feb. 2, 2016**

(54) **HEADSET**

(71) Applicants: **Pui Tong Kwan**, Hong Kong (HK);
XiangHui Kong, Guangzhou (CN); **Yu Zhao**, Guangzhou (CN)

(72) Inventors: **Pui Tong Kwan**, Hong Kong (HK);
XiangHui Kong, Guangzhou (CN); **Yu Zhao**, Guangzhou (CN)

(73) Assignee: **ADVANCED ELECTRONIC AND MEDICAL INDUSTRIES COMPANY LIMITED**, Cheung Sha Wan, KL (HK)

(**) Term: **14 Years**

(21) Appl. No.: **29/513,272**

(22) Filed: **Dec. 30, 2014**

(51) LOC (10) Cl. **14-01**

(52) U.S. Cl. **D14/205**
USPC .....
